UNITED STATES PATENT OFFICE.

BENNETT ROBY PAINE, OF HAMDEN JUNCTION, OHIO.

DESIGN FOR A BOTTLE.

SPECIFICATION forming part of Design No. 28,687, dated May 24, 1898.

Application filed March 14, 1898. Serial No. 673,873. Term of patent 14 years.

To all whom it may concern:

Be it known that I, BENNETT ROBY PAINE, a citizen of the United States, residing at Hamden Junction, in the county of Vinton and State of Ohio, have invented and produced a new and original Design for Bottles, of which the following is a specification, reference being had to the accompanying drawings, which form a part thereof, and in which—

10 Figure 1 is a side view of a bottle, showing my new design. Fig. 2 is a top or plan view of the same, and Fig. 3 is a sectional view taken on the line $x-x$ of Fig. 1.

As shown in the drawings, the leading or 15 material feature of my design consists of a body A, which is triangular in horizontal cross-section and hollow or tubular, having exteriorly-flat and vertically-parallel sides a^2 , extending to a flat top a , forming a horizontal plane, from which extends a cylindrical 20 vertical neck b with straight parallel sides. Said body has a flat bottom a' , between which

and the flat horizontal top a the vertical parallel sides a^2 extend. The sides of the body thus conjointly form a triangle in cross-section having flat and parallel terminal ends. At the top of the cylindrical vertical neck b is a horizontal flat flange b' , projecting laterally from the vertical parallel sides of said neck, as shown, and having a straight peripheral edge.

Having fully described my invention, what I claim as new, and desire to secure by Letters Patent, is—

The design for a bottle, substantially as 35 herein shown and described.

In testimony that I claim the foregoing as my invention I have signed my name, in presence of the subscribing witnesses, this 10th day of March, 1898.

BENNETT ROBY PAINE.
